UNITED STATES PATENT OFFICE.

ALONZO B. CONDE, OF ALBANY, NEW YORK.

DESIGN FOR A COVERED COOKING-PAN.

SPECIFICATION forming part of Design No. 22,782, dated September 12, 1893.

Application filed August 1, 1893. Serial No. 482,121. Term of patent 7 years.

To all whom it may concern:

Be it known that I, ALONZO B. CONDE, of the city and county of Albany, in the State of New York, have invented and produced a new and original Design for Covered Cooking-Pans, of which the following is a specification, reference being had to the accompanying drawing, which forms part of said specification.

o The accompanying drawing, which is herein referred to and forms part of this specification, shows a perspective view of my covered cooking-pan.

The leading feature of my design consists of an oblong rectangular body composed of a main part and a cover having the shape and ornamentation shown in the accompanying drawing.

As represented in the drawing, A designates the main part of my cooking-pan whose horizontal section is an oblong figure of a rectangular form and whose sides and ends have a slight inclination outwardly, so as to make the top of said part larger than its bottom. Each end—of which only one is shown—has two angular lines, 1, which, beginning at a lower corner, extend upwardly toward the top of said part near the middle of the end: each of said ends is provided with handle, 2, of an oval

form, said handles occupying a position near the lower part of the end and in the middle of said lower part of the end. A flange, 3, extends outwardly near the top of said main part, and is continued around the opposite sides of the latter.

B designates the cover of my cooking-pan which is made to conform to the horizontal outline of the top of the main part A of said cooking-pan. Around the lower edge of said cover, there is a bead, 4. At each end of said cover, a handle, 5, is located near the middle of the end. Said handle has an oval form and is attached to the cover B in any manner suitable therefor.

C designates the bail, which, has at or near its middle, a hoop-shaped center, 6, from the lower side of which arms, 7, extend tangentially in opposite directions, and at the outer end of each arm a hook-shaped lug, 8, depends.

What I claim as new, and desire to secure by Letters Patent, is—

The design for a covered cooking-pan substantially as herein shown and described.

ALONZO B. CONDE.
